CLAIM

The ornamental design for an alarm for patients in hospitals or the like, as shown and described.

DESCRIPTION

FIG. 1 is a perspective view of an alarm for patients in hospitals or the like showing our new design, with the rod broken away to indicate indeterminate length;

FIG. 2 is a left side elevational view thereof, with the cords broken away for ease of illustration;

FIG. 3 is a top plan view thereof;

FIG. 4 is a bottom plan view thereof.

FIG. 3

FIG. 4
